UNITED STATES PATENT OFFICE.

JOHN DIETZ, OF CINCINNATI, OHIO, ASSIGNOR TO THE JOHN DIETZ MANUFACTURING COMPANY, OF CINCINNATI, OHIO, A CORPORATION OF OHIO.

OPERATING MECHANISM.

1,073,409.

Specification of Letters Patent. Patented Sept. 16, 1913.

Application filed March 13, 1911, Serial No. 614,210. Renewed June 13, 1913. Serial No. 773,558.

To all whom it may concern:

Be it known that I, JOHN DIETZ, a citizen of the United States, and a resident of Cincinnati, in the county of Hamilton and State of Ohio, have invented certain new and useful Improvements in Operating Mechanism, of which the following is a specification.

My invention relates to improvements in operating mechanism and more particularly to improved means for operating washing and wringing devices.

The object of my invention is to provide simple, compact, convenient, efficient and durable means for easily operating washing and wringing devices mounted upon the same base or frame.

Another object of my invention is to provide operating mechanism for a washing machine adapted to be driven by a motor mounted upon the machine, and means whereby a wringer may be operated when desired by the same source of power which actuates said operating mechanism.

Another object of my invention is to produce operating mechanism for a washing machine which is adapted to be driven by electrical or other motive power, means whereby a wringer may be started, driven in reverse directions and stopped at the same time the washing machine is being driven, means for throwing the washing machine into and out of operation while the wringer is being operated, and means whereby the lid or support of the washing machine may be raised to open position without interfering with the operating mechanism of the wringer, and without having to turn off the source of power to raise said lid or support.

My invention consists in providing in combination with a motor, operating mechanism comprising a chain of gears, a crank shaft driven thereby, a telescopic shaft also driven thereby, gearing on said telescopic shaft, and a shaft driven by said gearing.

My invention also consists in means whereby said crank shaft and said shaft may be thrown into and out of operative engagement with said driving power, either simultaneously or successively.

My invention also consists in the parts, combination and subcombination of parts and in the peculiar and particular construction, location and arrangement of parts

with relation to the washing machine of the type herein illustrated, as set forth and claimed.

In the accompanying drawings which serve to illustrate my invention: Figure 1 is a side elevation of a washing machine equipped with my invention. Fig. 2 is an end elevation of the washing machine equipped with my invention. Fig. 3 is a side elevation of a washing machine equipped with my invention, the machine being shown in open position. Fig. 4 is an enlarged detail view of the mechanism adapted to drive the wringer. Fig. 5 is a detail plan view of the clutch mechanism adapted to throw the operating shaft of the washing machine into operation. Fig. 6 is a detail sectional elevation illustrating the wringer operating mechanism. Fig. 7 is an enlarged detail view of the male clutch member of the wringer operating mechanism. Fig. 8 is a detail view illustrating one of the pinion gears employed in the driving mechanism for the wringer. Fig. 9 is a detail elevation of the bracket to which the motor is attached, said bracket being mounted upon the lid or support of the washing machine. Fig. 10 is a detail view of right angled shaft employed in connecting the wringer operating mechanism to the mechanism adapted to drive the washing machine. Fig. 11 is an elevational view of the driving gear wheel, which is adapted to mesh with the pinion gear of the motor. Fig. 12 is a cross sectional view taken through the sprocket wheel and clutch of the washing machine drive mechanism. Fig. 13 is an elevational view of the bracket to which the main operating arm is pivoted.

In the embodiment of my invention as illustrated and which shows a preferred construction, 1 represents the body of a washing machine of the ordinary construction, supported on legs 2. The body or tub 1 is provided with the usual rub boards 3 and 4, the washing machine being of the double rub board or reciprocating rubber type. The rub boards are pivoted in the usual manner, the lower one 3 being pivoted in the tub 1, and the upper rub board being pivoted in the lid or support 5 of the washing machine.

An arm 6 is fastened to the lower rub board 3 and extends to the crank arm 7 on

the shaft 8 of the driving mechanism. Connected to said arm also is a pitman rod 9 which connects to a vertical extending arm 10 fastened to the upper rub board 4 on the washing machine. This construction is of the ordinary type of washing machines employing the double rub board. Thus when the shaft 8 is driven, the crank arm 7 is driven, thereby imparting a reciprocating action to the upper rub board 4 of the washing machine, and also a reciprocating action to the lower rub board 3 of the washing machine.

The lid or support 5 is hinged at 11 in the customary manner, and is also provided with the usual door 12 at the top thereof. A chain 13 is provided to prevent the lid from being opened too far, said chain being fastened at one end to the tub 1, and at the other end to the lid or support 5 of the washing machine. Thus it is seen that the washing machine proper is built in the ordinary manner.

A wringer 14 is securely mounted at one end of the tub 1 of the washing machine, and is built after the ordinary type of wringer, with the exception that the shaft or stem 15 of the lower roller 16 of the wringer is allowed to extend beyond the frame of the wringer to one side thereof.

Operating mechanism of the washing machine will now be described.

I provide a bracket 17 of suitable design and mount same upon the lid or support 5 of the washing machine, said bracket being constructed to accommodate the necessary shafts and motor which will be described.

A motor 18 is mounted upon the bracket 17 and is provided with a pinion gear 19, which is adapted to mesh with a large gear wheel 20. The large gear wheel 20 is best illustrated in Fig. 11 where it is seen that it is provided with a bevel pinion gear 21 at one side and a sprocket pinion 22 at the other side. Said gear wheel 20 is mounted upon the right angled shaft 23. One end 24 of said shaft 23 is adapted to enter the boss 25 on the bracket 17 as best shown in Fig. 9. The right angled shaft is shown in detail in Fig. 10. The end 24 of the shaft 23 may be pivotally secured or held in the boss 25 in any desired manner preferably by lock nut 24', said boss 25 acting as a bearing for said shaft also. The bracket 17 is also provided with upright supporting standards 26 and 27 in which is mounted a driving or crank shaft 8. The driving shaft 8 has a sprocket 29 mounted at one end, and a crank arm 7 at the other end. The sprocket 29 and sprocket pinion 22 are connected by means of a sprocket chain 30, and are thus driven together. The sprocket 29, however, is mounted loosely upon the driving shaft 8, and is disposed upon said shaft directly above the sprocket pinion 22. Now to cause

the sprocket 29 to operate and thereby operate the shaft 8, it is necessary to provide a clutch to be operated by hand when it is desired to operate the rubbers 3 and 4 of the washing machine.

The clutch mechanism is as follows: I provide a bracket 28 on the lid 5 of the washing machine adjacent the middle of the side of said lid. The said bracket 28 is provided with an upwardly extending portion 31, which is best shown in Figs. 5 and 13. The gear extension 31 is bifurcated, and forms a pivot 32 for the main operating lever 33. To prevent the operating lever 33 from being moved too far, I provide another extension 34 on the bracket 28 which is provided with a slot 44 therein, which is adapted to receive a latch which will be described. Mounted on the end of the shaft 8 I provide a male clutch member 35, which is provided with an annular groove 36. The said clutch member 35 is slidably mounted on said shaft, preferably splined thereto, and allowed to slide longitudinally along said shaft. The sprocket 29 is provided with the female member 37 of the clutch. A spring 38 bears against the sprocket 29 and the clutch member 35 and normally holds said clutch member out of engagement with the clutch member 37 on the sprocket wheel 29. The end of the operating lever is bifurcated to form a yoke 33' which fits into the annular groove 36 on the male clutch member 35.

The operating lever 33 is provided with a pivoted handle 39 which is pivoted at 40 to the main operating lever 33. It is the purpose of this pivoted handle 39 to act as a latch, it being provided with an extension 41 at the end thereof, which is adapted to extend down through an opening 42 in the main operating lever 33 and engage with the slot or notch 44 in the extension 34 on the bracket 28. A spring 43 is preferably provided between the pivoted handle 39 and the main operating lever 33. Thus the extension 41 on the handle 39 is always held in engagement with the top edge of the extension 34 of the bracket 28. Thus when it is desired to cause the sprocket 29 to drive the shaft 8, thereby operating the rub boards of the washing machine, it is first necessary to throw the handle portion of the operating lever 33 outwardly, thereby throwing the clutch members 35 and 37 into engagement with each other, and causing the shaft 8 to operate, due to the fact that the clutch member 35 is always turning with said shaft 8, it being splined thereto. The clutch members 35 and 37 will remain in engagement with each other until the pivoted handle 39 is forced downwardly, thereby releasing the latch extension 41 from the slot 44 and allowing spring 38 to force the clutch members 35 and 37 apart, thereby allowing the sprocket 29 to run loosely on the shaft 8.

and stopping the rub boards of the washing machine from operating.

In this type of washing machine when a wringer is adapted to be driven by the main driving mechanism, it is necessary that the connections for said wringer should not be affected by the raising of the lid of the washing machine. The mechanism for driving said wringer will now be described:

10 Mounted on the lower roller shaft 15 of the wringer is a bell shaped beveled gear 45, preferably pinned thereon, as best shown in Fig. 6. The shaft 15 is made smaller at the end shown at 46, upon which is mounted a shield disk 47, which is also provided with bearings 48. The shield 47 is loosely mounted upon said shaft 15, shown in Fig. 6 and is adapted to allow said shaft 15 to rotate therein. The shield 47 is provided with 20 small housings 49 diametrically opposite each other. In these housings are disposed pinion gears 50, said pinion gears being mounted upon a shaft 51 which passes through the bearings 48 on the shield disk 47. A detail of the pinion gears 50 is shown in Fig. 8, where it is seen that each pinion gear 50 is provided with a female clutch member 52 at one side thereof, and is provided with an annular groove 53 at the 25 other side thereof. The pinion gears 50 are loosely mounted upon said shaft 51 and are held in their proper position on said shaft by means of a set screw 54 passing through the housing 49 and entering a groove 53 in said pinion gears 50. Thus the set screws 54 are adapted to hold said pinion gears in their proper position on the shaft 51. When properly placed, the pinion gears 50 mesh with the bell shaped bevel gear 45 and are 30 adapted to drive said bell shaped gear when said pinion gears 50 are driven with the shaft 51.

It is seen that another clutch device must be employed to cause either one of said pinion gears 50 to operate with the shaft 51 in order to drive the bell shaped bevel gear 45, and thereby drive the wringer rollers. I, therefore, provide a slideable clutch sleeve 55, which is preferably splined by means of 40 spline 56, on the shaft 51, as best shown in Fig. 6. The clutch sleeve 55 is allowed to slide longitudinally on the shaft 51, although it is splined thereto, and is provided with male clutches 57 at each end thereof; 45 the clutch sleeve 55 is also provided with an annular channel 58 which is adapted to receive the end of an arm 59. The arm 59 is pivoted at 60 and is provided with a handle 61 on the other side thereof. Thus 50 when the arm 59 is rocked upon its pivot 60, it immediately slides the clutch sleeve 55 longitudinally on the shaft 51, and thereby throws one of the male clutches 57 into engagement with the female clutch on either 55 one of the pinion gears 50, which ever way

the arm 59 happens to be rocked. In this manner I am enabled to obtain an efficient reversing clutch mechanism for the wringer, inasmuch as I am enabled to operate either pinion gear 50 with the shaft 51, thereby 70 causing the bell shaped bevel gear 45 to rotate in either direction.

The operating means for shaft 51 will now be described: The right angled shaft 23 is provided with another extension 62, which 75 is provided with an annular groove 63 near the end. A hollow shaft 64 is adapted to cover the extension 62 of the right angled shaft 23, and is adapted to rotate thereon. A set screw 65 is provided in the hollow shaft 64, and is adapted to enter the annular groove 63 in the extension 62 of the shaft 23, and the hollow shaft 64 is thereby prevented from moving longitudinally relative to the extension 62. The shaft 51 is adapted to enter the hollow shaft 64, and extend therein a considerable distance. The end of the hollow shaft 64 is provided with a spline 66, which is adapted to slide in an elongated spline way 67 in the shaft 51. Thus it is 80 seen that the shaft connection between the wringer mechanism and the operating mechanism of the washing machine is a telescopic connection, the hollow shaft 64 and shaft 51 being adapted to slide relative to 85 each other, but always rotating with each other. At one end of the hollow shaft 64 adjacent the pinion gear 21 on the gear wheel 20 is mounted another pinion gear 68, which is adapted to mesh with said pinion 90 gear 21. The pinion gear 68 is pinned or otherwise securely fastened to the hollow shaft 64, and is adapted to drive said hollow shaft 64, the hollow shaft 64 in turn being adapted to drive the shaft 51 by means 95 of the spline 66.

The importance of providing a telescopic shaft arrangement as described, is readily seen when the lid or support 5 of the washing machine is raised, as shown in Fig. 3. 110 This figure clearly illustrates why the sliding arrangement of the hollow shaft 64 and shaft 51 is necessary, owing to the increased distance between the center of the gear 20 and the center of the shaft 15 of the lower roller 16 of the wringer.

By means of the set screw 65, the pinion gear 68 is always in engagement with the pinion gear 21, whether the lid or support 5 of the washing machine is open or closed. 115 Thus the hollow shaft 64 is always being driven with the gear wheel 20, thus driving the hollow shaft 64 and shaft 51.

When it is not desired to operate the wringer, the operating arm 59 may be left 120 in its central vertical or neutral position, where the clutch member 55 will not engage either of the pinion gears 50, thereby allowing the shaft 51 to move freely inside the pinion gears 50, and not operating the bell 125 130

shaped bevel gear 45, which operates the wringer.

It is readily seen by referring to Fig. 3 that when the lid or support of the washing machine is raised, the center of the gear wheel 20 is considerably lower than it is when the machine is closed. This, however, does not affect the shafts 64 and 51, inasmuch as the shield disk 47 which carries the bearings 48 for the shaft 51 is loosely mounted on the shaft 15 of the wringer, and is thereby allowed to rock upon said shaft and conform itself to the proper angle, to register with the shafts 64 and 51.

15 The weight of the mechanism is practically all placed at the pivoted point of the lid or support 5, thereby allowing the lid to be raised with little effort and balancing same in the open position, as well as in the closed. The motor 18 is mounted above the water line of the washing machine, thus preventing any water from falling thereon and interfering with the operation of the motor, but if desired the motor may be differently mounted upon the machine.

25 Many modifications of my invention may be made without departing from its spirit and scope, and I do not wish to be confined to the exact details shown.

30 What I claim as new and desire to secure by Letters Patent is:

1. In a device of the class described, a hinge support, a motor mounted thereon, a crank shaft, a chain of gears connecting said motor and crank shaft and adapted to be actuated by said motor, a telescopic shaft, a pinion actuated by said chain of gears, a pinion on said telescopic shaft, adapted to be actuated by said first mentioned pinion, 35 an operating lever and connecting parts for throwing said crank shaft into and out of operative communication with said motor and a bracket to which said lever is pivotally connected, substantially as set forth.

40 2. In a machine, the combination of a motor, a pinion actuated by said motor, a gear wheel, a sprocket pinion and pinion simultaneously actuated by said gear wheel, actuating means connected to said sprocket pinion, a telescopic shaft, and a pinion fixed on said telescopic shaft and adapted to be actuated by said second mentioned pinion, substantially as set forth and for the purposes specified.

45 3. In a machine, a motor, a pinion actuated thereby, a gear wheel actuated by said pinion, a pinion and actuating means connected to said gear wheel adapted to be simultaneously actuated thereby, a telescopic shaft, a pinion fixed theron and adapted to be actuated by said second mentioned pinion, substantially as set forth and for the purposes specified.

50 4. In a machine, a motor, a pinion actuated thereby, a gear wheel actuated by said

pinion, actuating means on said gear wheel, a pinion on said gear wheel, a telescopic shaft, a pinion fixed on said telescopic shaft and adapted to be actuated by said second mentioned pinion, a second pinion on said telescopic shaft, and a gear wheel suitably mounted and adapted to be actuated by said second pinion, substantially as set forth and for the purposes specified. 70

5. In a machine, a motor, a pinion actuated thereby, a gear wheel actuated by said pinion, actuating means on said gear wheel, a pinion fixed on said gear wheel, a telescopic shaft, a pinion thereon actuated by said second mentioned pinion, two additional pinions on said telescopic shaft, a gear wheel suitably mounted and adapted to be alternately actuated by said last mentioned pinions, and means for throwing said last mentioned pinions, respectively, into and out of operative engagement with said gear wheel alternately to produce alternating reversible rotary movements, substantially as set forth. 75

6. In a machine, a motor, a pinion actuated thereby, a gear wheel actuated by said pinion, a sprocket pinion mounted and adapted to move with said gear wheel, a shaft suitably mounted, a sprocket loosely mounted on said shaft, a sprocket chain 90 mounted on said sprocket and sprocket pinion and adapted to communicate power from said sprocket pinion to said sprocket, and means for throwing said sprocket into and out of operative engagement with said shaft, substantially as set forth and for the purposes specified. 95

7. In a machine, a motor, a pinion actuated thereby, a gear wheel actuated by said pinion, a sprocket pinion actuated by said gear wheel, a shaft suitably mounted, a sprocket loosely mounted on said shaft, a sprocket chain mounted on said sprocket and sprocket pinion and adapted to communicate power from said sprocket pinion to said sprocket, and a clutch adapted to throw said gear wheel into and out of operative engagement with said shaft, substantially as set forth and for the purposes specified. 105 110

8. In a device of the class described, a hinged support, a bracket thereon, a motor on said bracket, a train of gears, a crank shaft adapted to be actuated by said motor through said train of gears, a right angled shaft pivotally mounted in said bracket, a beveled pinion driven by said motor loosely mounted on said right angled shaft, a telescopic shaft having one end adapted to revolve upon one end of said right angled shaft, a beveled pinion adapted to engage 115 and be driven by the first mentioned beveled pinion, and a shaft adapted to be driven by said telescopic shaft, substantially as set forth and for the purposes specified. 120 125

9. In a device of the character described, 130

1. a bracket, a motor mounted thereon, a pinion actuated thereby, a crank shaft mounted thereon, a train of gears adapted to communicate movement from said pinion to said crank shaft, means connected to said pinion adapted to operate other mechanism, and means for throwing said crank shaft into and out of operative engagement with said train of gears.
10. 10. In a device of the character described, a bracket suitably mounted, a crank shaft on said bracket, a sprocket loosely mounted on said shaft, means to impart movement to said sprocket, a clutch on said shaft, a main operating lever adapted to engage said clutch, a latch on said operating lever adapted to hold said clutch in engagement with said sprocket and a spring adapted to disengage said clutch and said sprocket, when the latch is released, substantially as set forth.
15. 11. In a device of the character described, a motor, a crank shaft, a sprocket loosely mounted on said crank shaft, a train of gears adapted to communicate movement from said motor to said sprocket, a clutch on said crank shaft, a main operating lever pivotally mounted and having a yoke adapted to engage said clutch, a handle on said operating lever and a pivotally mounted latch forming part of said handle, a spring between said latch and the main operating lever, and a catch adapted to be engaged by said latch, substantially as set forth and for the purposes specified.
20. 12. In a machine of the character described, a bracket mounted upon the rear end of a hinged support, a motor mounted upon said bracket and adapted to assist in balancing said support, operating mechanism connected to said motor and to the interior mechanism of the machine, and also connected to an auxiliary machine, whereby both machines may be operated in unison or alternately without disconnecting the source of power.
25. 13. In a device of the character described, a bracket, a motor mounted thereon, a crank shaft adapted to operate mechanism, a shaft, and means for simultaneously communicating power from said motor to said shaft and to said crank shaft respectively, without disconnecting the source of power to said motor, substantially as set forth.
30. 14. In a device of the character described, a bracket having a boss, a motor mounted thereon, a crank shaft mounted thereon, a right angled shaft mounted on said boss, a hollow shaft rotatably mounted on said right angled shaft, means for communicating power from said motor to said crank shaft and said hollow shaft, a shaft partly in said hollow shaft, and adapted to be rotated by said hollow shaft and to move longitudinally relatively to said hollow shaft
35. 15. In a device of the character described, a bracket, a crank shaft journaled therein, a motor mounted thereon, a pinion actuated by said motor, a right angled shaft mounted on said bracket, a gear wheel loosely mounted on said right angled shaft, a sprocket pinion actuated by said gear wheel, a hollow shaft mounted on said right angled shaft, and held in fixed relation longitudinally thereof, but adapted to rotate on said right angled shaft, a shaft telescoping with said hollow shaft and adapted to rotate therewith, a shaft, a gear wheel mounted thereon, and pinions mounted on said telescopic shaft and means to throw said pinions into and out of engagement with said gear wheel to alternately operate the same in reverse directions, substantially as set forth and for the purposes specified.
40. 16. In combination with a machine of the class described, having shafts, a support, an electric motor mounted on said support, operating mechanism for said machine adapted to be driven by said motor, a chain of gearing connecting said motor and operating mechanism, and a shaft driven by said motor adapted to operate said shafts, substantially as set forth.
45. 17. In a device of the class described, the combination with a motor, of operating mechanism, a crank shaft driven thereby, a telescopic shaft also driven thereby, gearing on said telescopic shaft, and a shaft driven by said gearing.
50. 18. In combination with a machine of the class described, operating mechanism adapted to be connected to and disconnected from the machine, a telescopic shaft adapted to be driven by said operating mechanism and adapted to operate a shaft at its other end, said shaft and means for connecting and disconnecting said shaft into operative engagement with said telescopic shaft.
55. 19. In combination with a machine, a support, an electric motor mounted on said support, mechanism mounted on said support and directly connected to said electric motor, said mechanism adapted to operate the machine, and means whereby the mechanism mounted on said support of said machine is thrown into and out of operative connection with said motor, said means consisting of a clutch, a frame, an operating lever pivoted upon a frame mounted on said support of the machine, and means on said lever for holding said clutch in the proper position to operate the machine.
60. 20. The combination with a machine of operating mechanism therefor, shafts, one shaft having an extension, a bell shaped beveled gear mounted on said shaft, a shield
- 100 105 110 115 120 125 130
- 70 75 80 85 90 95 100

disk mounted over said beveled gear having bearings therein and loosely mounted upon said shaft, pinions adapted to engage said bell shaped beveled gear, a telescopic shaft 5 driven by the operating mechanism of the machine, part of which shaft is adapted to pass through said pinions, said pinions loosely mounted thereon, a clutch slidably mounted on said telescopic shaft and adapted to clutch either pinions, thereby driving said pinions with the telescopic shaft, said telescopic shaft allowing said support of the machine to be raised without affecting the driving mechanism of said shaft, substantially as set forth.

21. In a machine, driving mechanism, shafts driven thereby, a telescopic shaft operatively connected to said shafts, and a clutch and lever adapted to throw said telescopic shaft into and out of operative connection with said shafts.

22. In a device of the character described, a motor, operating mechanism driven thereby, a gear wheel actuated by said mechanism, a sprocket pinion mounted to move with said gear wheel, a sprocket chain engaging said sprocket pinion and sprocket, and adapted to actuate the latter, a crank shaft on which said sprocket is mounted and

a clutch for throwing said sprocket into 30 and out of operative engagement with said crank shaft.

23. In a device of the class described, a machine having a hinged support, a bracket on the hinged end of said support, a motor 35 mounted on said bracket, a crank shaft mounted on said bracket and driven by said motor, a telescopic shaft also driven by said motor, gearing on said telescopic shaft, a shaft driven by said gearing, and a clutch 40 adapted to engage and disengage said gearing to reverse the direction of rotation of said shaft, substantially as set forth.

24. In a device of the class described, in combination with a motor, a crank shaft 45 driven thereby, a telescopic shaft also driven thereby, a shaft driven by said crank shaft, pinions loosely mounted on said telescopic shaft, a gear wheel fixed on said shaft, a clutch adapted to engage and disengage said pinions, and an arm and handle adapted to move said clutch into and out of engagement with said pinions respectively, substantially as set forth.

JOHN DIETZ.
